CLAIM

The ornamental design for a baby support pillow, as shown and described.

DESCRIPTION

FIG. 1 is a top, front, and right side perspective view of a baby support pillow showing our new design, the undisclosed left and rear sides being mirror images of the right and front sides, respectively;

FIG. 2 is a vertical cross-sectional view thereof, taken along line 2—2 of FIG. 3;

FIG. 3 is a top plan view thereof, the undisclosed bottom being plain and unornamented;

FIG. 4 is a top, front, and right side perspective view of an alternate embodiment thereof, the only difference being in the absence of semi-circular cut-outs for resting on the legs of a person, and the undisclosed left and rear sides being mirror images of the right and front sides respectively;

FIG. 5 is a vertical cross-sectional view of the alternate embodiment thereof, taken along line 5—5 of FIG. 6; and

FIG. 6 is a top plan view of the alternate embodiment thereof, the undisclosed bottom being plain and unornamented.
